JOHN DITTRICK

ATT'G.

UNITED STATES PATENT OFFICE.

JOHN DITTRICK, OF PERTH, ONTARIO, CANADA.

CHAIR-LEG EXTENSION.

1,272,636.

Specification of Letters Patent. Patented July 16, 1918.

Application filed April 9, 1918. Serial No. 227,538.

To all whom it may concern:

Be it known that I, JOHN DITTRICK, a subject of the King of Great Britain, and resident of the town of Perth, in the Province of Ontario, Dominion of Canada, have invented certain new and useful Improvements in Chair-Leg Extensions, of which the following is a specification.

This invention relates to improvements in chair leg extensions, and the objects of the invention are to devise a simple and effective device by which the legs of a chair may be extended to convert it into a high chair, suitable for children, and it consists essentially of the improved construction, herein-after described in detail in the accompanying specification and drawing.

In the drawings:

Figure 1 is a perspective view of the extension device on a chair.

Fig. 2 is a vertical section of one leg.

Fig. 3 is a cross section.

Fig. 4 shows a modification of the extension members.

In the drawings, like characters of reference refer to corresponding parts in the several figures.

Referring to the drawings, A represents a chair of any usual construction, and B represents my extension members each comprising an extension piece 10 of wood or other convenient material, and an engaging member 11 adapted to fit around the leg of the chair, this member being conveniently formed of metal in U-shape and cross section, and rigidly attached to the extension piece 10 by screws, nails or the like.

The engaging member 11 is formed with projecting sides 12, and diagonally opposite the engaging member are connected together and held in position on the chair leg by suitable tie rods 13, the chair being engaged with bails or shackles 14 connected to the extensions 12.

The tie rods 13 may be of any suitable material, of cord or string if desired. Suitable means are provided for tightening them, the means I have shown comprising turn buckles 15.

It will be seen that the pressure exerted on the chair leg at the tie rods 13 will cause the extension members B to be held firmly in position and to construct a rigid support for the chair leg.

In the form shown in Fig. 4, thumbscrews 21 extend into the engaging members 21. These thumbscrews are connected to the tie rods and thereby permit adjustment of the length of the same.

The engaging members in either form of the invention, if made of sheet metal, will be flexible and may be conformed to the shape of any leg whether square, flat, or round.

As many changes could be made in the above construction and many apparently widely different embodiments of my invention, within the scope of the claim, constructed without departing from the spirit or scope thereof, it is intended that all matter contained in the accompanying specification and drawings shall be interpreted as illustrative and not in a limiting sense.

What I claim as my invention is:

A chair leg extension device consisting of extension pieces having upper horizontal surfaces, engaging members secured to the extensions and forming sockets to receive the chair legs and tie rods between the engaging members, the parts being constructed and arranged so as to provide a complete article capable of immediate use.

In witness whereof I have hereunto set my hand in the presence of two witnesses.

JOHN DITTRICK.
